W. F. RAVENOR

SAFETY FEED FOR OIL BURNERS

Filed June 5, 1924

INVENTOR

Wilfred Francis Ravenor

By *Wilfred Francis Ravenor*

UNITED STATES PATENT OFFICE.

WILFRED FRANCIS RAVENOR, OF VANCOUVER, BRITISH COLUMBIA, CANADA.

SAFETY FEED FOR OIL BURNERS.

Application filed June 5, 1924. Serial No. 717,991.

To all whom it may concern:

Be it known that I, WILFRED FRANCIS RAVENOR, a subject of the King of Great Britain, and a resident of the city of Vancouver, in the Province of British Columbia, Canada, have invented certain new and useful Improvements in Safety Feeds for Oil Burners, of which the following is a specification.

10 My invention relates to improvements in safety feeds for oil burners, and the object of my invention is to provide a simple, practical, and efficient means whereby the oil feed is controlled solely by the heat created by the burner with which it is connected, or other heat creating means, consequent upon which the flow of oil to the burner is automatically prevented when the flame becomes extinguished from any cause whatever, thus enabling such burners to be used with great safety and adding greatly to their convenience and utility.

Oil burners generally have the disadvantage that in the event of the flame becoming extinguished the oil continues to flow to the burner unless it is stopped by some mechanical contrivance provided for the purpose and this, of course, is liable to get out of order and become useless and ineffective. 25 Thus, in oil burners where such a means as is indicated in the preceding paragraph is not associated or embodied or in those provided with mechanical contrivances as above referred to the possibility exists of the flame becoming inadvertently extinguished, such as by being blown out by a gust of wind, and if this is not noticed the oil continues to flow and spread with the resultant danger of serious fire through ignition of the unno- 30 noticed overflow when reigniting the burner.

This defect is entirely eliminated according to the present invention, a clear understanding of which will be had on referring to the accompanying drawing in which the figure 35 illustrates one form, more or less diagrammatically, in which the invention may be carried out.

1 indicates generally a tube of substantially elongated U-form one leg 2 of which 50 is open while the other leg 3 is closed at its upper end, being provided, however, at any suitable point adjacent its extremity with an orifice 4 forming a feed outlet between which and the burner (not shown), whether 55 retort, generator, vaporizer, wick pan, or other analogous device, oil feed communi-

cation may be established. The upper end of the leg 3 is preferably of reduced area, as shown, and indicated by the numeral 11. The orifice 4 may also be in the end closure 60 5.

6 indicates an oil supply tank from which extends a valved pipe 7 the end of which is disposed above the open end of the leg 2 of tube 1 while 8 indicates an overflow tank 65 connected by a pipe 9 to an orifice 10 in the leg 2 positioned intermediate its length and slightly above the normal level of the oil in the tube 1.

In operation oil is carried in the tube 1 with the levels in the respective legs 2 and 3 maintained under static head intermediate the length of the legs, the body of oil in the tube being kept up by regulated feed from the supply tank 6 through the valved 70 pipe 7. The oil in leg 3 being within the zone of heat, indicated by the dotted line and numeral 12, created by the burner, shown conventionally and indicated by the numeral 13, the volume of the oil in leg 3 is 75 increased by the heat tending to vaporize the lighter fractions therein, thereby greatly expanding the total volume in leg 3 so that the level of the oil in leg 3 rises during operation of the burner and the oil flows 80 through the orifice 4 to the burner 13. Should, however, the flame be extinguished the heat zone no longer exists and consequently the oil in leg 3 returns to its normal level so that no oil can flow out through the 85 orifice 4, while at the same time the rise in the level of the oil in leg 2 due to the continuous feed from pipe 7 is restricted to the height on the leg of the orifice 10 through which the accumulating oil in leg 2 over- 90 flows into the tank 8.

It should be here mentioned that the heat to which the column of oil in leg 3 is subjected, which is herein referred to as that existing within the burner heat zone, may be 100 heat created by any suitable means other than the burner; in other words, the heat zone may be created by any suitable heat conductor applicable to the purpose.

From the foregoing it will be seen that I 105 have devised a safety feed for oil burners which is simple, practical, and efficient and entirely eliminates danger through overflow of the oil from the burner should it become inadvertently extinguished.

What I claim as my invention is:

1. The combination with an oil burner, of

- a feed pipe having its delivery end terminating in a straight vertical portion exterior of the burner proper closed at its upper end and provided with an orifice adjacent the closed end, said pipe being adapted to contain oil a portion of which extends as a vertical column into said delivery end the head of the column being normally below and spaced from the said orifice and forming with the walls and closed end of the said delivery end a chamber exterior of the burner wherein the column expands under a heat zone influence to spill over at the orifice into the burner proper.
2. The combination with an oil burner, of a feed pipe having its delivery end terminating in a straight vertical portion exterior of the burner proper closed at its upper end and provided with an orifice adjacent the closed end, said pipe being adapted to receive a regulated flow of oil a portion of which extends as a vertical column into said delivery end the head of the column when cold being normally below and spaced a predetermined distance from the orifice and forming with the walls and closed end of the said delivery end a chamber exterior of the burner wherein the column expands under a heat zone influence to spill over at the orifice into the burner proper, and means for maintaining the head of the column when cold at the predetermined distance from the orifice irrespective of the continuity of the regulated oil flow.
3. The combination with an oil burner, of a feed pipe having its delivery end closed and provided with an orifice adjacent the closed end and associated with the burner proper exteriorly thereof, said pipe being adapted to contain oil a portion of which extends as a vertical column into said delivery end the head of the column when cold being normally below and spaced a predetermined distance from the orifice and forming with the walls and closed end of the said delivery end a chamber wherein the column expands under a heat zone influence to spill over at the orifice into the burner proper, means for feeding a regulated supply of oil to said pipe, and an overflow associated with the pipe arranged to prevent flooding of the same.
4. The combination with an oil burner, of a feed pipe arranged in substantially elongated U-shape one leg being closed at its end and the other leg being open, the said closed end being connected to the burner exteriorly thereof within the burner heat zone and provided with an orifice adjacent the end closure, said pipe being adapted to contain a body of oil a portion of which extends as a vertical column within each leg respectively, the head of the column in the closed leg being when cold normally below and spaced a predetermined distance from the orifice and forming with the walls and closed end of the said delivery end a chamber wherein the column expands under the heat zone influence to spill over at the orifice into the burner, means for feeding a regulated supply of oil into the open leg to maintain the oil body constant, and an overflow tank associated with said open leg having a connection extending therebetween connected to the said open leg at a point intermediate its mouth and the head of the oil column therein, said tank being below the point of connection.
5. The combination with an oil burner, of a feed pipe arranged in substantially elongated U-shape one leg being closed at its end and the other being open, the said closed end being disposed exterior of the burner within the burner heat zone and provided with an orifice adjacent the end closure, said pipe being adapted to contain oil a portion of which extends as a vertical column within each leg respectively, the head of the column in the closed leg being when cold normally below and spaced from the orifice and forming with the walls and closed end of the said delivery end a chamber exterior of the burner wherein the column expands under the heat zone influence to spill over at the orifice into the burner proper.

Dated at Vancouver, B. C. this 29th day of May, 1924.

WILFRED FRANCIS RAVENOR.
